UNITED STATES PATENT OFFICE.

CURT F. ZIMANSKY, OF SAN FRANCISCO, CALIFORNIA, ASSIGNOR TO G. W. PRICE
PUMP AND ENGINE COMPANY, OF SAN FRANCISCO, CALIFORNIA.

IMPELLER SPACER AND BUSHING.

Application filed February 11, 1924. Serial No. 692,027.

To all whom it may concern:

Be it known that I, CURT F. ZIMANSKY, a citizen of the United States, residing in the city and county of San Francisco and 5 State of California, have invented a new and useful Improvement in an Impeller Spacer and Bushing, of which the following is a specification.

My invention relates to improvements in 10 rotary well pumps and particularly to the mounting of the runners thereof upon the shaft of the pump.

The primary object of my invention is to 15 provide an improved construction in well pumps.

Another object is to provide an improved means for rigidly securing the runners of a well pump against longitudinal movement relative to the drive shaft.

20 A further object is to provide an improved construction designed to prevent wear upon the shaft within the bearings of the pump bowls.

A still further object is to provide an im- 25 proved construction adapted to facilitate the construction and assembly of the pump and to insure the accurate positioning of the parts.

I accomplish these and other objects by 30 means of the device disclosed in the drawings forming a part of the present specification wherein like characters of reference are used to designate similar parts through said specification and drawings and in which,

35 The figure is a vertical section of a rotary pump showing my improved construction.

Referring to the drawing the numeral 1 is used to designate in general a pump mounted upon a discharge casing 2 within a well 40 casing 3. The pump consists of a plurality of bowls 4 each of which includes a bearing portion 6 within which is mounted a drive shaft 7 which extends upwardly to the top of the well through a suitable shaft casing 8 centrally disposed within the discharge casing 2. Runners or impellers 9 are secured 45 upon the shaft 7 within the bowls 4 for forcing water upwardly through the discharge casing 2 in the well known manner.

50 One of the chief difficulties encountered in assembling a pump of the type described is to rigidly secure the runners upon the shaft in correct relation to their respective bowls and to prevent longitudinal movement 55 along the shaft when under heavy load. My

present invention is therefore directed to an improved construction adapted to facilitate the assembly of the parts and to rigidly secure the runners against longitudinal movement. I accomplish this in the following 60 manner.

The bearing portions 6 are made of a diameter considerably greater than the diameter of the shaft 7 to receive sleeves 11 mounted upon the shaft. The runners 9 are feathered upon the shaft 7 by means of suitable keys engaging keyways 12 formed upon the shaft at appropriate points so as to normally permit a slight longitudinal movement of the runner.

In assembling the pump the 70 runners are compressed against the adjacent sleeves 11 which are made of a length adapted to obtain a correct spacing of the runners. This is accomplished in the following manner. The bowls 4, runners 9, and sleeves 11 are placed upon the shaft in their correct relation and collars 13 and 14 permanently secured upon the shaft above the bearing portion within the uppermost bowl, and below the lowermost runner respectively. The uppermost sleeve 11 abuts against the collar 13 and the uppermost runner in turn abuts against the lower end of said sleeve. The 75 succeeding sleeves 11 are engaged between

80 succeeding runners as shown in the drawing. The collar 14, secured below the lowermost runner is provided with an extension 16 axially recessed and internally threaded to receive a threaded portion 17 of a bushing 18 mounted upon the shaft between the collar 90 85 14 and the runner. The bushing 18 is initially receded to its extreme position within the threaded recess of the collar 14. When the several parts are assembled as above described, the bushing 18 is advanced from the collar to firmly compose the runners and sleeves against the collar 18, and the bushing thereafter secured against further rotation by means of a set screw 19 or other suitable

95 securing means, in this manner rigidly securing the runners against longitudinal movement upon the shaft and holding said runners in accurately spaced relation.

In addition to holding the runners in rigid spaced relation, the sleeves perform the further function of preventing wear upon the shaft 7 within the bearing portion 6. As above mentioned, the bearings 6 are made of a diameter considerably greater than the diameter of the shaft. Each bearing is pro- 100 105 110

vided with a bushing 21 secured therein, said bushings being machined to form a running fit with the sleeves 11 extending therethrough. The pressure applied upon 5 the runners and the sleeves by means of the threaded bushing 18 is sufficient to cause the sleeves to rotate with the shaft and runners and to prevent the entrance of water between the sleeves and the runners and thus 10 between the sleeve and the shafts.

This feature of my invention is of importance for the reason that one of the most frequent causes of trouble with pumps of the type described is the wearing of the bearings 15 within the bowls of the pump. The sand and grit frequently carried by the water as pumped from the well works into the bearing with the result that both the shaft and the bearing portion of the bowl is rapidly 20 cut out. This wear of the bearing increases the natural tendency of the shaft to whip within its casing and as a result the pump has to be withdrawn from the well and expensive replacements often have to be made. 25 By my improved construction the wear which would normally occur upon the shaft will be taken up by the sleeves 11 and, in case the wear becomes excessive, only the sleeve will have to be replaced. In a similar way, the bushing 21 within the bearing portion of the bowl takes up wear which would otherwise damage the bowl itself and this member may be readily replaced, but as 30 the use of bushings in bearings of all kinds 35 are well known no claim is made to this specific element of the construction I have disclosed.

From the above description it will be readily seen that I have provided an improved construction which materially facilitates the assembly of the pump and which results in a rigid and accurate securing of the runners upon the shaft in such manner as to prevent wear upon the shaft during 45 operation.

Having thus described my invention what I claim as new and desire to secure by Letters Patent is,

1. The combination with the bowls and shaft 50 of a rotary well pump of a runner feathered upon the shaft within each bowl; a retaining collar secured upon the shaft; spacing mem-

bers mounted upon the shaft for positioning the runners with respect to the collar; a member secured upon the shaft adjacent the runner remote from the collar; and a bushing screw threaded onto said member, said bushing being movable upon said threads to engage and compress the runners and spacing members against the retaining collar for 60 rigidly securing said runners against longitudinal movement upon the shaft. 55

2. The combination with the drive shaft of a well pump of a plurality of runners feathered upon the shaft; a retaining collar secured upon the shaft above the runners; spacing members mounted upon the shaft adjacent each runner; and securing means for rigidly securing the runners and spacing members against longitudinal movement 70 along the shaft, said means comprising a collar secured upon the shaft below the runners, and a bushing threaded upon the collar and movable relative thereto to compress the runners and spacing members against 75 the retaining collar. 65

3. In a device of the character described, a securing member comprising a collar secured to a pump shaft provided with pump runners; a threaded extension formed upon the collar; and a bushing movably mounted upon the shaft and arranged to engage the threads of the extension whereby said bushing may be advanced to rigidly secure the pump runners against longitudinal movement 80 upon the shaft. 85

4. In a device of the character described, a securing member mounted upon a pump shaft provided with pump runners, said securing member comprising a collar secured 90 upon the shaft and having an internally threaded recess axially disposed in one end thereof; and a bushing disposed in one end thereof; and a bushing mounted upon the shaft and provided with external threads arranged to engage the threads of the collar whereby said bushing may be advanced 95 along the shaft relative to the collar for securing the runners against longitudinal movement along the shaft. 100

In witness whereof I hereunto set my signature.

CURT F. ZIMANSKY.
